UNITED STATES PATENT OFFICE

2,103,744

MACHINE FOR GAME PLAYING

Clifford R. Dumble, Arlington, Mass., assignor,
by mesne assignments, to Joseph L. Zelaskow,
New York, N. Y.

Application June 14, 1933, Serial No. 675,719

36 Claims. (Cl. 273—121)

This invention relates to an improved amusement device and particularly to such a device of the pin board type, wherein balls may be rolled over a board having groups of pins surrounding 5 openings, the latter having different scoring values. Balls passing through certain of the openings may also be effective in operating suitable playing disk return means adapted to give a series of playing disks to the person using the 10 machine, these disks permitting the person again to play the game. Thus, a game of this type may be played by inserting a disk in a suitable receiving mechanism and by actuating handles or manually operable controls to cause the movement 15 of the balls into proper position and the successive projection thereof over the pin board itself. If the balls pass into certain openings, a return mechanism is actuated to permit a plurality of disks to be supplied by the machine so that the player may use them in repeated operations 20 of the machine. Often players of games of this type become very skilled and used to the peculiarities of individual machines so that they may manipulate the machines in an unfair manner to obtain more frequent return of disks than are warranted. Under such conditions, the machine may be subjected to wear and rough handling of undue severity. Thus machines of 25 this type may be tilted to permit the rolling of the balls into openings effective to return playing disks, while in numerous cases shaking or vibration of the machine may have a similar effect, or a properly timed repetitive manipulation of the disk receiving slider of the machine may 30 be effective in causing unmerited premiums.

The present invention is effective in affording an improved, accurately operating machine of this general type, particularly adapted to afford the same chances of obtaining a return of disks 40 under all normal operating conditions, and being substantially immune to improper operation. Thus, a machine of this type is arranged to avoid the obtaining of undeserved disks when it is tilted or either the whole machine or the disk 45 receiving portion thereof is vibrated or shaken. Furthermore, the present invention affords a novel arrangement of trip elements operable by balls receivable in a certain series of openings in the pin board; accordingly, a machine of this 50 type rather than returning one or two disks in response to the reception of balls by various openings, may give a larger number of disks when balls are received in each opening of a combination or set of openings, such as three 55 openings. Thus interest in the game may be

stimulated. In a typical embodiment of the invention, four sets of three openings each may be afforded to return disks, each set of three openings being arranged to give a different number of playing disks, if desired. To permit these results, the present invention affords an arrangement of associated instrumentalities effective to permit the operation of the game device in the conventional manner, these instrumentalities including various associated electrical switches and 5 circuits as well as cooperating mechanisms. A tilting control may be afforded to interrupt flow of electrical current through the main operating circuits when the machine is tilted, as well as to cause the energization of a warning light, thus 10 to prevent operation of the return mechanism due to tilting of the machine, in an attempt to evade the conditions imposed by regular operation of the machine.

Furthermore, switch means may be afforded to 20 preclude possibility of manipulation of the disk receiving portion or slider of the mechanism to cause unmerited operation of the return mechanism or a repeated operation of the same when but a single operation is proper. Associated with 25 the electrical means and included therein are a plurality of trip operated switches associated with each of the sets of openings above referred to. Thus, when balls are received in each opening of a given set, corresponding switches may be closed 30 to permit the flow of current to the return mechanism. This mechanism itself may be provided with electrical control means effective to an un- 35 warranted repeated operation of the disk returning mechanism despite any jiggling or shaking of the machine.

In the accompanying drawings:

Fig. 1 is a front elevation of a machine constructed in accordance with this invention, the lower portions of the legs being broken away; 40

Fig. 2 is a top view of the pin board portion of the machine, the upper cover or casing thereof having been removed;

Fig. 3 is a plan view of the front end of the machine with the pin board and related parts 45 removed and with parts broken away;

25 Fig. 21 is a wiring diagram for the assembly of Figs. 16 and 17.

To facilitate an understanding of this invention, I will first generally describe a well-known type of game device to which the principles of this invention are applied. This machine or game device comprises a generally rectangular casing 1, which may be mounted on suitable legs 2 and provided with an inclined cover 4 in the form of a suitable glass panel, so that the movement of the balls within the casing may be readily witnessed. A mirror or advertising panel 5 may be disposed at the rear of the machine. Disposed in the upper part of the rectangular casing 1 is the pin board proper, designated by numeral 10. This board is provided with a marginal frame adapted to act as a guide for the balls and is slightly inclined upwardly toward the rear so that the balls ejected toward the rear wall or abutment surface 11 normally roll down toward the front end of the machine where they may be received in slots 13. The board 10 is provided with a series of openings 14 of a size to receive a suitable ball. Disposed on the board in various spaced positions as well as in groups or rows about or in the vicinity of the openings are pins 16 against which a ball may strike or roll, thus being diverted from its original path and adding to the interest of the game.

At one side of the board 10 a groove or alley 17 is provided along which a ball may be impelled to the playing surface of the board. A spring 19 mounted on an upright pin or stud 20 at the outlet end of alley 17 is arranged to prevent return movement of a ball from the body portion of the board 10 to the alley. Beneath the pin board 10 is a lower board 38 (Fig. 5) forming the bottom of a ball receiving chamber. Thus balls passing downwardly through openings 14 or slots 13 ultimately pass into this chamber, as will be more fully explained, and may roll downwardly into a receiving compartment at the front right-hand corner of the machine. A swinging arm 36 provides an end plate 32 movable in this chamber to engage a single ball and elevate to the region of a transverse, substantially semi-

circular passage or trough 33 through which the ball passes into the alley 17, this general arrangement of the ball return mechanism being well known and conventional in the art. A handle 29 is provided to actuate the elevator parts 31 and 32 through linkage 34.

A plunger 35 extends into the front end of alley 17 and is normally held in the position shown in Fig. 2 by a coiled spring (not shown) disposed within casing 36. The plunger is provided with a handle 37 on the outside of the machine, this handle being operable to cause retraction of the plunger so that it may be returned to or snapped back to its normal position by action of the spring within the housing 36, thus driving a ball 15 along the alley 17 past spring 19 in the direction of the curved border surface 11 of the pin board, whence the ball may roll forwardly over board 10, normally passing into engagement with certain pins 16 and perhaps falling into one of the 20 openings 14 or perhaps continuing to the lower front end of the board and being received by one of the slots 13.

A sliding panel 40 may be mounted beneath the pin board proper 10; suitable supporting 25 brackets 41 engage the edges of the panel 40 to hold it in this position. A tension spring 42 (Fig. 5) is normally effective in drawing the panel 40 toward the front of the machine where it may engage a suitable stop. In its normal position the panel 40 underlies slots 13 and certain openings 14 so that the balls passing into the slots or openings are held in view of the player until a subsequent operation is performed. Special means which will be described and which are associated with the panel 40 are effective in holding the balls positioned in other openings so that the total number of balls passing in the openings after a given period of play or plays with a set of balls of determined number may be 40 readily ascertained. Ordinarily the scores which are counted for rolling the balls into the individual openings are indicated on the board itself so that the player can readily calculate his score. Colored circles F may be painted on the board 10 45 to identify the sets of openings which are particularly significant in operating the disk returning mechanism; thus each set of openings may be identified by different colored circles.

At the front of the machine is a light T disposed beneath a suitable glass panel. Upon the panel a suitable word such as "Tilted" may be printed so that the glass behind this word is illuminated when the light T is energized, the tilting control device being effective to stop normal operation of the playing disk returning mechanism and causing energization of this light if the machine is tilted to an appreciable angle, as will be more fully explained.

Now referring in detail to the disk-receiving 60 mechanism, it is to be understood that a fixed bracket 50 receives a slider 51, this plate, as shown, having a circular opening 52 (Fig. 3) over a smaller opening on bracket 50 to provide a generally annular rabbet upon which the margin of the disk may rest. As shown, a projection 54 is provided on the bracket to prevent the operation of the machine with an ordinary circular slug having, for example, the shape of a conventional coin, but only permitting operation 65 of the machine with a special playing disk having a cut or slot in its margin to fit the projection 54.

A tension spring 56 is connected to a transverse bar 57 at the inner end of the slider 51. 75

The bar 57 engages a depending lug 59 on sliding panel 40 so that the panel 40 may be slid toward the back of the machine when a disk is inserted in the recess 52 and passes under the conventional latching mechanism (not shown), thus permitting the slider to push the lug 59. A swinging switch element 61 affords one contact of a switch A adjoining the slider 51. The member 61 is normally held in position by the bar 57, but when the slider 51 is pushed inwardly the element 61 may swing so as to separate its contact from the fixed contact 68 of the switch A, a spring 63 tending to cause the switch to open. After the bar 57 is returned to its normal position, it engages an insulating block 60 at the end of element 61, thus automatically to cause closing of the switch. Accordingly, the flow of current through switch A is interrupted only when the slider 51 is pushed inwardly to cause movement of the panel 40.

At the rear of the machine (Figs. 5 and 14) are a plurality of fixed magnets D arranged in parallel circuits, as will be described; each of these magnets is associated with a swinging armature 65 pivotally mounted on a bracket 69 depending from the board 10. A spring 71 normally holds each armature 65 in the retracted position shown in Fig. 5 wherein the armature serves as a lock to hold a swinging support 70 in the illustrated tilted position.

The plate 70 supports a mercury switch C which, when in the position illustrated in Fig. 5, is effective in closing contacts between leads 74 and 75. When the magnet D is energized, the locking armature 65 is moved out of the illustrated position so that the adjoining end of swinging support 70 moves downwardly to break the circuit between leads 74 and 75. When the parts are in this position and panel 40 is moved toward the rear of the machine, a depending lug or ear 80, carried by this panel, engages the downwardly inclined portion 70a of member 70 to swing the latter and the switch C to its normal position, whereupon the spring 71 may be effective in moving the locking armature 65 under the opposite end of member 70 to support the latter in its normal tilted position.

Beneath certain of the openings 14 are trigger elements 90 which are in effect extensions of swinging brackets 91 supporting mercury containing tubes or switches 93, these switches being inserted in series with consecutive sections of leads 75. Preferably there may be several sets of switches 93 arranged in series. Thus, there may be four sets of three openings provided with trigger elements 90, the switches of each set being in series so that the closing of the three switches due to the reception of balls on the corresponding three triggers 90 is effective in closing a circuit in order to operate the playing disk returning mechanism in the manner which will be more fully described.

Fig. 5 illustrates the normal position of a trip or trigger 90 in relation to the opening 14. Disposed beneath the opening is a depending sheet metal member 92 of substantially U-shaped cross section. The trip 90 and its continuation, which carries an upstanding stop 94 for switch element 93, extends through the opening between the legs of this hood 92.

Fig. 15 illustrates the position of parts 90 and 93 when a ball has been received in the corresponding opening 14. As shown in full lines in this figure, the member 90 is tripped so that stop 94 engages panel 40 as a stop, the circuit between lead sections 75 being closed in this position of

the parts and the ball being supported in the opening 14. It is thus evident that the trip elements 90 are effective in holding the balls in the corresponding openings 14, while portions of the panel 40 are effective in supporting the balls in the other openings. Thus after a set of balls has been projected onto the board, the balls which have been received in the scoring openings 14 may be readily observed, and the player can calculate his score. After this has been done, and when the slider 51 is again actuated to move the panel back, each element 90 is moved rearwardly with the panel into the position shown in dot and dash lines in Fig. 15, thus moving away from the hood 92 so that sufficient room is afforded to permit the ball to pass through the opening thus provided onto the board 30. Thus when the panel 40 is slid toward the rear of the machine it moves the trips 90 out from the positions wherein they retain balls in corresponding openings 14, while it moves to cause openings formed in the panel 40 itself to register with the remaining openings 14 as well as with the slots 13. Thus return of the balls to the elevating and projecting instrumentalities is permitted.

Mounted on board 10 between magnets D there is a conditioning switch 73 carried on a support 170 similar to the support 70 of switches C. A lug or cam element 180 similar to the elements 80 is effective in temporarily tilting this switch and closing the circuit between its leads 200 and 205 when the panel 40 reaches its rearmost position. Normally the lug 180 is spaced from switch 73 so that the latter is opened. This switch is arranged to condition the tilting control after the device has been tilted in order to permit resumption of normal operation.

The tilting control illustrated in Figs. 10 and 11 has a master switch 100 in series with the various sets of switches 93. This control is provided with a swinging support 99 carrying the master switch 100 having leads 101, 102 and 103 extending into the same and arranged so that a circuit may be closed between either leads 101 and 102 or between leads 101 and 103. Adjoining the master switch 100 is a standard 105 fixedly connected to a base plate 107 which is secured by fastenings 109 to a suitable horizontal board or lower closure member 108 that may, for example, be disposed beneath the board 30 (Fig. 1). Accordingly, tilting of the machine, including the board 108, out of horizontal position causes inclination of the upright 105. Fixed on the upright are a series of brackets 110 which support a plurality of mercury switch elements 111, these elements each having a slight inclination from the vertical in each one of four different directions and containing a quantity of mercury such that the tipping of the plate 107 and consequent inclination of the upright 105 to a slight angle may be effective in bringing one of the elements 111 to a circuit closing position. The closing of this switch is effective in energizing the magnet M which causes tilting of the master switch 100 against the action of spring 104 to open the circuit between leads 101 and 102 and close the circuit between leads 101 and 103.

Fig. 11 illustrates this tilted position of the master switch wherein its support may be locked by the swinging latch 114 which is actuated by the leaf spring 115.

For an interval after such a tilting operation the master switch may remain locked in the position shown in dot and dash lines. An electromagnet R is disposed adjoining the upper end of 75

latch 114 and is capable of being energized, as will be described, to move the latch out of engagement with the support 99 permitting the spring 104 to move the support 99 and master switch to 5 the position shown in full lines.

Upon the base 108 I also provide a mercury switch 116 which is fixedly mounted in relation to the base and is connected in series with the switch 100 through lead 101. The switch 116 is 10 arranged to prevent tilting of the entire machine to cause inclination of the switch 100 when it occupies its dotted line position and consequent closing of the circuit between leads 101 and 102, which might result in operation of the disk returning mechanism, as will be more fully described in connection with the operation of the machine.

The disk-receiving mechanism is arranged to release a disk from recess 52 of slider 50 when 20 the latter moves inwardly to move the panel 40 and permit the balls to drop through openings 14 and slots 13. The released disk is received by a circular hopper 120 (Figs. 6 and 7). Rotatable in this hopper is a star wheel 121 having semi-circular recesses cooperating with the inner wall of hopper 120 in defining compartments in which a series of the playing disks or tokens may be received.

Secured to the wheel 121 is a ratchet pinion 30 122. Above pivot 122, an arm 119 is independently rotatable and carries a pawl 123 effective to turn wheel 122 and star wheel 121 in an anti-clockwise direction, as viewed in Fig. 6. The end of arm 119 carries an element 124 having a 35 V-shaped recess, in which the pin 118 on arm 51 of the disk-receiving mechanism may engage (Fig. 3), thus to cause an oscillatory movement of arm 119 and a movement of pawl 123 sufficient to move the pinion wheel 122 a single step in 40 response to actuation of slider 51.

The bottom of hopper 120 is provided with outlet passages 125 disposed over disk grouping and dispensing wheels 130 which are pivotally mounted on horizontal shafts and have radial recesses 131 (Fig. 8) to receive a plurality of the playing disks. The recesses 131 upon one side of each of 45 the wheels 130 may normally be filled with disks, while on the opposite side of the wheels these recesses may be open. On the first-named side of each wheel a suitable substantially semi-circular hoop element 135 may be provided to prevent outward movement of the disks from the recesses as the latter move toward an inverted position, the elements 135 terminating adjoining the lowest 50 portion of the periphery of each wheel so that when a recess arrives at the bottom of the wheel it is free to emit the disks contained therein into a discharge passage 136. Thence the disks fall into a sliding drawer 138 accessible from the 55 exterior of the machine (Fig. 1).

Suitable mechanism is provided for operating the various dispensing wheels in response to the actuation of a set of triggers 90. For this purpose a plurality of solenoids S are provided, the solenoids corresponding in number to the dispensing wheels 130. Each solenoid is provided with a plunger 140 connected by a link to the outer member 141 of a ball clutch unit such as shown in Fig. 9, so that movement of a plunger 140 in 60 one direction, i. e., to the right in Fig. 7, may be effective in causing the rotation of the clutch element 141 and the adjoining element 142 which is fixed to one of the dispensing wheels 130. Accordingly the energization of the solenoid may be effective in causing rotation of the corresponding 65

dispensing wheel 130 through a fraction of a revolution to permit release of disks from a recess 133.

Normally a spring 152 retains the latch 150 in engagement with a notch on a control wheel 151 which is associated with each dispensing wheel 5 130 to hold the latter in a fixed position.

A magnet N may be energized to move the latch 150 out of engagement with the wheel 151, thus to permit movement of wheels 151 and 130 by the corresponding solenoid S. In order to prevent possible movement of the dispensing wheel beyond the proper fraction of a revolution which will permit the dispensing of disks from one recess 131, a swinging stop pawl 154 is provided with a cam lug 155 engageable with the pivotal connection 156 of the plunger link and the ball clutch mechanism so that movement of the plunger to the left may permit the pawl 154 to drop into engagement with the periphery of wheel 151 to act as a stop in engaging an upstanding abutment 20 surface on the wheel. Thus overrunning of the wheel 130 is positively prevented.

At the end of its path the plunger 140 may engage a movable contact 160 of a switch B, which will be more fully described.

Next referring to the wiring diagram, current may be received from any source of supply, as, for example, a suitable battery, through a lead 200 which is associated with a return lead 201. One side of lead 201 may be connected by a 30 branch 201^a to a light T. The opposite side of this light is connected to the lead 103 which terminates in a contact at one end of the master switch 100 of the tilting control mechanism. From the switch tube 100, lead 101 extends to 35 switch tube 116; from the latter the lead 101^b extends to a connection with lead 200 and to a lead 101^c that is connected to one side of magnet M. A lead 106 extends from the latter to each of the switch tubes 111. The opposite contacts of the latter are connected in parallel by a lead 204 which extends to the opposite side of the magnet M, which in turn is connected to the branch 201^b of lead 201. Branch 201^b is connected to the magnet R associated with latch 114, and the opposite side of magnet R is connected by lead 205 to conditioning switch 73 (Fig. 14) at the rear of panel 40, the latter being in turn connected to lead 200. The lead 201 is connected by a branch 201^c to the fixed element 68 of switch A, the element 61 being connected to a lead 207. 40

The lead 102 extends from the master switch 100 of the tilting control and has branches 102^a connected to leads 75 joining the trigger switches 93 of each series. Branches 75^a of lead 102 are 55 connected to the magnets D associated with the respective main switches C and from each magnet D a lead 209 extends to the fixed contact of switch B, the movable contact 160 of the latter being connected by a lead 210 to the solenoid S, the opposite side of the solenoid being connected by lead 212 to the main switch C.

The lead 210 is extended to join the lead 207, and leads 214 and 215 connect a magnet N in parallel with the solenoid S.

The general operation of a machine of this character will now be described with particular reference to the wiring diagram and with general reference to the other portions of the mechanism, the operation of individual instrumentalities and subassemblies having been previously discussed in respective instances.

Assuming that a suitable playing disk is disposed on the recess portion 52 of the slider mechanism, the slider 51 is pressed inwardly to op- 75

erate the bar 57, thus momentarily opening switch A. Under such a condition of the parts current can not flow through the solenoid S and leads 210 and 212. Accordingly, jiggling or vibratory movement of the slider 51 and panel 40 and closing of switches 93 does not affect a solenoid S. Inward movement of the slider 51 is normally effective through bar 57 and lug 59 in pushing the panel 40 toward the rear of the machine, thus permitting the balls to pass downwardly from the slots 13 in the pin board as well as from the openings 14, which are provided with triggers 90 and the remaining openings. At the same time, should a switch C be open, a member 80 may engage the part 70^a of the member 70 to return the latter to its normal tilted position shown in Fig. 5, the latch 65 snapping into a position to support the member 70 and switch 73 in this illustrated position. Thus, if the switch C has previously been opened, it will be closed by this operation. The switch 73 is also momentarily closed by movement of panel 40.

The closing of switches C and 73 conditions the circuits extending between the corresponding series of trigger switches 93 and the corresponding solenoid S. Obviously when the slider is fully actuated in this manner the playing disk is received within the bowl 120 and then the star wheel is rotated a fraction of a revolution. Thus, disks are distributed in the various recesses provided by the periphery of the star wheel and the disks are received by the radial recesses in wheel 130. The slider 51 may then be released by the operator to close switch A, the spring 56 returning this slider to its original position; the balls under these conditions have rolled to the chamber adjoining elevator 32, having rolled from the board 30 into this chamber. Under these conditions each switch C is closed, while the trigger switches 93 and the solenoid-operated switches B may be open. The handle 37 may then be operated to cause the movement of one of the balls through the trough 33 into the alley 17, whereupon the operator is ready to start playing.

The handle 37 is pulled toward the operator and released, the spring associated with this handle being effective in causing the plunger to strike the ball and cause its movement through the alley 17 past spring 19 onto the pin board 10. The ball normally may strike the curved abutment surface 11 at the rear of the pin board and then roll downwardly, normally striking certain of the pins 16 and either falling in one of openings 14 or passing downwardly to be received by one of the slots 13. In this position of the parts the ball may be supported by the panel 40 and/or triggers 90 so that if a competitive game is being played by two or more players, the positions of the balls may be observed to permit keeping of score. Successive balls may be brought into playing position and moved by the plunger 37 in the same general manner as has been described. If the player fails to cause balls to move to each of the holes 14 of one set to engage the corresponding triggers 90, the balls will remain in the described position, resting on the triggers 90 and/or panel 40 in openings 14 or slots 13 until another disk is inserted on the slider 51 and the same again actuated, whereupon the panel 40 will be moved to permit the balls to drop downwardly onto the inclined bottom board 30.

While the balls are supported in openings 14 or slots 13, if the player or an accomplice should attempt to obtain the return of disks by tilting of the machine to cause the balls to roll into the

openings, a slight tilting is sufficient to cause the closing of the circuit between the leads extending to one of the tubes 111, this being effective in permitting the flow of current from lead 200 through one side of the magnet M, one of the tubes 111, and lead 204 to the other side of magnet M and thence through lead 201.

Accordingly magnet M is energized to cause movement of the master switch 100 out of normal position and the closing of the circuit between leads 101 and 103. Under these conditions current may flow from lead 200 and its branch 101^b, leads 101, switch 100, lead 103, light T and leads 201^a and 201. Thus the light T is energized to indicate that the device is being tilted. This light may be disposed at the front of the machine, as shown in Fig. 2. If the machine has been tilted in this manner it can not be reconditioned for disk dispensation until another disk has been inserted, whereupon the panel 40 is moved, closing switch 73; and magnet R may be energized to move the latch 114, thus permitting the return of master switch 100 to its normal position.

After the tube 100 has been moved to its dotted line position, as shown in Fig. 11, and locked in that position by the latch 140, a player might maneuver the machine by tilting to cause the balls to roll into openings corresponding to one set of trip members 93 and then tip the entire machine so that the switch tube 100, although in its dotted line position, as shown in Fig. 11, would be inclined sufficiently to close the circuit between leads 101 and 102 thus permitting operation of the disk returning mechanism in the normal manner which will be described. However, the switch 116 is so arranged that when the entire machine is tilted in this manner, the circuit between leads 101 and 101^b is automatically broken thus preventing flow of current to the disk returning mechanism.

When a player in normal play is successful in causing balls to engage each one of the trigger elements 90 of one of the sets of these elements, each of the corresponding switches 93 is moved to its closed position. Since the switches A and C are already in closed position, current may pass from lead 200 through lead 101, switch 100, lead 102, lead sections 102^a and 75 and switches 93 of the circuit corresponding to the depressed triggers 90. From the last switch 93 of this series the current may pass to the conditioning switch C and thence to solenoid S and to magnet N. The latter releases the locking wheel 151 and the corresponding dispensing wheel 130 while the solenoid S moves the plunger 140 toward the left, as viewed for example in Fig. 4, thus turning wheel 130 through the ball clutch mechanism 141, 142. This results in releasing a set of playing disks from one of the recesses in wheel 130 so that they pass downwardly through chute or outlet 136 into drawer 138 from which they may be taken by the player. Thus the player may repeat play several times, employing the playing disks thus received.

As the plunger 140 approaches the end of its path, it closes switch B, thus causing current to flow through magnet D which is effective in causing movement of the main switch C out of its normal position so that the circuit through the solenoid is automatically interrupted and possibility of repeated actuation of the wheel 130 and repeated dispensation of premiums is avoided. As has been previously described, when the machine is again operated the movement of

the panel 40 is effected to ensure the return of main switch C to its normal operating position.

Under conditions of competitive play two or more players having several playing disks may 5 play this game in turn, each projecting the balls over the pin board 10 and computing the scoring values of the openings into which they may roll balls. When a player receives additional disks due to the depression of the triggers of one set 10 by the balls which he has rolled onto board 10, the additional playing disks permit him to operate the machine a number of additional times and to receive an increased score. It is thus evident that the arrangement of the trigger elements 90 in sets adds to the uncertainty of the game when played by a single player starting with a set of playing disks.

Fig. 13 illustrates an optional switch arrangement which may be substituted for the switches 20 111. In this embodiment of the invention a single tilting switch may be mounted on any suitable support and may comprise a cylindrical holder 300 in which there is a pool of mercury 301 beneath a horizontally disposed wire loop 302, 25 the loop being connected to a lead 306 at the top of the receptacle and an opposite lead 307 having a contact immersed in the mercury 301. With this embodiment of the invention, slight tilting of the receptacle 300 causes contact between the mercury body 301 and a portion of the 30 hoop 302, thus closing the circuit between leads 306 and 307 which may be connected to the magnet M to operate the master switch 100 in the manner already described.

35 Figs. 16 to 21 inclusive illustrate an optional disk returning mechanism wherein the movement of the dispensing wheel may be effected through a series of manually operated plungers 161^a, 161^b, 161^c or 161^d. Within the casing a substantially vertical duct 162 is arranged to receive playing disks from the slider 51. These playing disks therefore become stacked in the lower part of the duct 162 which is supported on a bracket 163 secured upon a supporting frame 164. An opening is provided at the lower end of duct 162 so that disks may pass into circular recesses 165 in a dispensing wheel 166 having a vertical axis of rotation. The support 164 is arranged below the major portion of the wheel 166, thus providing bottoms for recesses 165, but adjoining the duct 162 a depending passage or outlet 169 (Fig. 16) is afforded to supply playing disks to a chute 172 which is provided with a spring-held closure 171 which may be actuated 45 to release the disks into the hand of the player.

50 Each of the plungers 161^a, 161^b, 161^c and 161^d is connected to a horizontally disposed push rod 174. Thus in the illustrated embodiment of the invention there are four of these push rods located one 55 above the other. The inner end of each of these rods is provided with a laterally projecting arm 175 connected to a tension spring 176. Thus the spring normally tends to move the corresponding plunger and push rod to the position illustrated 60 in Figs. 16 and 17 wherein the upturned end of the push rod provides a stop member engaging the front wall of the cabinet as an abutment.

65 Upon the side of each of the rods 174 are a plurality of teeth 177 providing a rack engaging the teeth of a fragmentary pinion 181, a portion of the periphery of which is extended to afford an outstanding plate 182. Secured upon the lower face of the plate 182 is a pawl 183 (Figs. 19 and 20) pressed by a spring 184 into engagement with ratchet teeth of a ratchet wheel 185, the latter be-

ing connected to a spindle 186 which is coaxial with and secured to the dispensing wheel 166. Accordingly when a plunger, as, for example, the plunger 161^a, is pushed inwardly, the corresponding push rod 174 is effective in rotating the corresponding pinion 181, thus acting through the pawl 183 to rotate spindle 186 and dispensing wheel 166 in an anti-clockwise direction, as viewed in Fig. 16. Thus one of the openings 165 may be moved over the outlet 169 to emit playing disks into 10 chute 172.

15 As shown in Figs. 16 and 17, the plungers may be provided in different lengths corresponding to segmental portions of the wheels 166 occupied by a different number of recesses 165. Thus the shortest plunger 161^a may be effective in turning the wheel 166 so that the playing disks from one recess are dropped into the chute 172, while the plungers 161^b, 161^c and 161^d may be actuated to supply playing disks from two, three and four 20 recesses, respectively.

25 Preferably each of the plungers normally is locked in its outermost position by a spring-held latch element 190 engaging ratchet teeth 191 upon the side of the push rod 174. Accordingly the plunger can not be actuated to cause operation of the dispensing mechanism unless the latch 190 is moved from its normal position. For that purpose a series of magnets 192 may be provided adjoining the respective latches 190, a suitable 30 vertical support 193 being arranged to hold the magnets and latches in proper vertically spaced relation.

35 Each magnet 192 may be connected in series with the trigger switches 93 in the same manner that the solenoid S is connected when an electrically operable dispensing mechanism is employed. Thus, as shown in Fig. 21, the general arrangement of the wiring diagram may be the same as illustrated in Fig. 12, the connections to the tilting control switches being as previously described and the switch C being arranged in the general manner previously illustrated. From the switch C the lead 214 may be connected to the magnet 192, the latter being connected to the opposite side of the line 210. At the end of the path of each push rod 174 is a cutout switch B¹ corresponding to the switch B, this switch being connected by lead 209^a to the magnet D and having its opposite side connected to the lead 210. Thus when a plunger and corresponding push rod move inwardly to turn a dispensing wheel 166 and cause the same to drop playing disks into the chute 172, the corresponding switch B¹ energizes the magnet D, thus temporarily opening the corresponding switch C and deenergizing the circuit of magnet 192. The circuit remains in this condition until another playing disk is disposed upon the slider 51, whereupon the slider and panel 40 are pushed toward the rear of the machine and the switch C is again closed, in the manner previously described, to condition the circuit so that the magnet 192 may again be energized when all of the switches 93 in series therewith are closed.

45 I claim:

50 1. A machine of the class described comprising a pin board, means associated with the board adapted to be actuated when articles, such as balls, rolled over the board engage said means, electrical switches operable in response to actuation of said means normally to cause the closing of an electrical circuit, a playing disk-returning mechanism normally operable in response to current passing through said circuit, a master switch in said circuit, and control means therefor, said 55

means being operable when the board is tilted out of normal position to cause opening of the master switch and interruption of the flow of current through the circuit, whereby operation of the 5 disk-returning mechanism in response to actuation of said first-named means is prevented.

2. A machine of the class described comprising a board having a plurality of openings therein, trigger elements associated with certain openings, 10 each arranged to be actuated when an article, such as a ball, passes into the corresponding opening, a switch operatively associated with each trigger element, an electrical circuit in which said switch is located, playing disk-returning mechanism 15 operable in response to flow of current through said circuit, a master switch in said circuit, and control means for said master switch responsive to tilting of the board and effective to cause opening of the master switch and prevent 20 flow of current to the disk-returning mechanism.

3. A machine of the class described comprising a board having a plurality of openings therein, trigger elements associated with certain openings, each arranged to be actuated when an 25 article, such as a ball, passes into the corresponding opening, a switch associated with each trigger element, an electrical circuit in which the switches are located, playing disk-returning mechanism operable in response to flow of current 30 through said circuit, a master switch in said circuit, and control means for the master switch including a receptacle containing a conductive liquid adapted to move into and out of circuit-closing position in response to slight tilting of 35 the board.

4. A machine of the class described comprising a board having a plurality of openings therein, trigger elements associated with certain openings, each arranged to be actuated when an article, such as a ball, passes into the corresponding opening, a switch associated with each trigger element, an electrical circuit in which said switch is located, playing disk-returning mechanism operable in response to flow of current 40 through said circuit, a master switch in said circuit, and control means for said master switch including a plurality of mercury containing tubes tilted in different directions in relation to each other and each arranged so that movement of the tube out of its normal tilted position is effective 45 in closing a control circuit, a magnet in said control circuit operable upon the closing thereof to open the master switch and interrupt flow of current to the disk-returning mechanism, thus to prevent operation of said mechanism 50 when the machine is tilted.

5. A machine of the class described comprising a board having a plurality of openings therein, trigger elements associated with certain openings, each arranged to be actuated when an article, such as a ball, passes into the corresponding opening, a switch associated with each trigger element, an electrical circuit in which said switch is located, playing disk-returning mechanism operable in response to flow of current through said circuit, a master switch in said circuit, control means operable upon tilting of the board out of normal position to open the master switch and interrupt flow of current through said circuit, 55 and a warning signal actuated upon operation of said control means to indicate that the machine is tilted and that the playing-disk mechanism accordingly is inoperable.

6. A machine of the class described comprising a pin board having a plurality of openings there-

in, trigger devices arranged in certain of said openings to be actuated by a ball rolling into these openings, switches associated with the respective trigger devices and arranged in series in a circuit so that the circuit may be closed 5 when all of the corresponding trigger devices are actuated, a playing disk-returning mechanism normally operative in response to the closing of said circuit, said disk-returning mechanism including a magnet in said circuit, and a dispensing 10 wheel rotatable through a fraction of a revolution in response to the energization of said magnet to emit a plurality of playing disks.

7. A machine of the class described comprising a pin board having a plurality of openings therein, trigger devices arranged in certain of said openings to be actuated by a ball rolling into these openings, switches associated with the respective trigger devices and arranged in series in a circuit so that the circuit may be closed 15 when all of the corresponding trigger devices are actuated, a playing disk-returning mechanism normally operative in response to the closing of said circuit said disk-returning mechanism including a solenoid in said circuit, a dispensing wheel rotatable through a fraction of a revolution in response to the energization of said solenoid to emit a plurality of playing disks, and a switch 20 operable in response to movement of the dispensing wheel and energization of the solenoid to 25 interrupt flow of current through said circuit after the dispensing wheel has moved sufficiently 30 to emit playing disks.

8. A machine of the class described comprising a trigger switch adapted to be actuated under 35 certain conditions of play, a playing disk-returning mechanism, including an electrically actuatable mechanism, in circuit with said switch, a main switch in said circuit, means operable in response to energization of the electrically actuatable mechanism to emit a set of playing disks, means operable thereafter to open said main 40 switch and prevent further operation of the electrically actuatable mechanism, and means to receive a playing disk and then to close the main 45 switch to permit repeated play and repeated operation of the disk-returning mechanism after another playing disk has been inserted in said last-named means.

9. A machine of the class described comprising 50 a pin board having a plurality of openings therein, a trigger device associated with one of said openings and adapted to be actuated when a ball is received in that opening, dispensing mechanism, an electrical circuit operatively connecting 55 the trigger device and the dispensing mechanism so that the mechanism may operate in response to actuation of said device, a slider shaped to receive a playing disk, mechanism operative in response to movement of the slider with a 60 playing disk thereon to direct balls for projection over the pin board, a switch in series with the trigger device and dispensing mechanism arranged to be opened upon movement of the slider so that vibratory movement of the slider can not 65 be effective in causing movement of the trigger device to close the circuit when the trigger device is not actuated by receiving a ball.

10. Disk-returning mechanism of the electrical- 70 ly operated type comprising a hopper, a dispensing wheel rotatable about a substantially horizontal axis beneath the hopper and having a plurality of radial recesses adapted to register with an outlet from the hopper and receiving playing disks therefrom, a closure member en- 75

- circling a portion of the dispensing wheel but arranged to permit emission of playing disks from one of said recesses as it approaches its lowermost position, and a solenoid having a plunger arranged to cause the rotation of the dispensing wheel through a fraction of a revolution to permit emission of disks from one of said radial recesses in response to each actuation of the solenoid.
11. Disk-returning mechanism of the electrical-ly operated type comprising a hopper, a dispensing wheel rotatable about a substantially horizontal axis beneath the hopper, and having a plurality of radial recesses adapted to register with an outlet from the hopper and receiving playing disks therefrom, a closure member encircling a portion of the dispensing wheel but arranged to permit emission of playing disks from one of said recesses as it approaches its lowermost position, a solenoid having a plunger arranged to cause the rotation of the dispensing wheel through a fraction of a revolution to permit emission of disks from one of said radial recesses in response to each actuation of the solenoid, a notched wheel secured to the dispensing wheel, a locking pawl normally engaging a notch in the wheel to prevent rotation of the dispensing wheel, and an electromagnet in circuit with the solenoid to move the locking pawl out of normal position to release the wheels and permit the dispensing wheel to rotate in response to energization of the solenoid.
12. Disk-returning mechanism of the electrical-ly operated type comprising a supply chamber, a dispensing wheel beneath the chamber and having a plurality of recesses to register with an outlet from the chamber and receive playing disks therefrom, means arranged to receive playing disks from one of said recesses, means to cause the rotation of the dispensing wheel through a fraction of a revolution to emit disks to said first-named means, a notched wheel connected to the dispensing wheel, a locking pawl normally engaging a notch in the wheel to prevent rotation of the dispensing wheel, an electromagnet to move the locking pawl out of normal position to release the wheels and permit the dispensing wheel to rotate, and a second pawl moved upon energization of the solenoid into position to catch against the edge of a notch upon said notched wheel to prevent overrunning movement of that wheel and the dispensing wheel.
13. A machine of the class described comprising a dispensing wheel having a series of recesses therein, means to supply playing disks to the recesses as they pass a given point during the rotation of the wheel, means adjoining another part of the wheel arranged to receive playing disks from the recesses, locking means normally effective to prevent rotation of the wheel, a playing board, a trigger device associated with the playing board, a switch adapted to be moved to closed position in response to movement of the trigger device, an electromagnet controlled by said switch and effective when energized to release the locking means thus to permit rotation of the dispensing wheel, and means to effect rotation of the dispensing wheel to cause the emission of playing disks from one of the recesses therein.
14. A machine of the class described comprising a dispensing wheel having a series of recesses therein, means to supply playing disks to the recesses as they pass a given point during the rotation of the wheel, means adjoining another part of the wheel arranged to receive playing disks from the recesses, locking means normally effective to prevent rotation of the wheel, a playing board, a trigger device associated with the playing board, a switch adapted to be moved to closed position in response to movement of the trigger device, an electromagnet controlled by said switch and effective when energized to release the locking means thus to permit rotation of the dispensing wheel, and means to effect rotation of the dispensing wheel to cause the emission of playing disks from one of the recesses therein.
15. A machine of the class described comprising a dispensing wheel having a series of recesses therein, means to supply playing disks to the recesses as they pass a given point during the rotation of the wheel, means adjoining another part of the wheel arranged to receive playing disks from the recesses, locking means normally effective to prevent rotation of the wheel, a playing board, a trigger device associated with the playing board, a switch adapted to be moved to closed position in response to movement of the trigger device, an electromagnet controlled by said switch and effective when energized to release the locking means thus to permit rotation of the dispensing wheel, means to effect rotation of the dispensing wheel to cause the emission of playing disks from one of the recesses therein, and a cut-off switch operatively associated with the electromagnet and operable in response to actuation of said last-named means to prevent repeated operation of the dispensing wheel in response to a single actuation of the trigger device.
16. A machine of the class described comprising a dispensing wheel having a series of recesses therein, means to supply playing disks to the recesses as they pass a given point during the rotation of the wheel, means adjoining another part of the wheel arranged to receive playing disks from the recesses, a manually controllable member to rotate the wheel, locking means normally effective to prevent rotation of the wheel, a playing board, a trigger device associated with the playing board, a switch adapted to be moved to closed position in response to movement of the trigger device, an electromagnet controlled by said switch and effective when energized to move the locking means out of its locking position thus to permit rotation of the dispensing wheel by said member, a switch operatively associated with the electromagnet and disposed at one end of the path of said member so that the switch is opened as the member approaches the end of its path thus preventing repeated operation of the dispensing wheel.
17. A machine of the class described comprising a trigger element, a trigger switch associated therewith, an electromagnet, a circuit connecting said trigger switch and electromagnet in series, a dispensing wheel having recesses to contain playing disks, means associated with the dispensing wheel to release playing disks when a recess reaches one point in its rotary path as the wheel is being rotated, locking means associated with the dispensing wheel and normally locking the same against rotation, said locking means being releasable in response to energization of the electromagnet due to the closing of the trigger switch, a main switch in series with the electromagnet and the trigger switch, and means op-

erative in response to rotation of the dispensing wheel to open the main switch and thus to deenergize the magnet which has been retaining the locking means out of its normal locking position.

5 18. A machine of the class described comprising a trigger element, a trigger switch adapted to be closed in response to movement of the trigger element, a dispensing wheel, said dispensing wheel having a series of recesses to hold playing 10 disks, means operatively connected to the dispensing wheel to release playing disks from successive recesses thereof when said recesses reach a given point during rotation of the dispensing wheel, locking means normally preventing rotation of the dispensing wheel, and electromagnetic means effective to release the dispensing wheel from the locking means in response to closing of the trigger switch.

15 19. A machine of the class described, comprising a trigger device, a trigger switch operable in response to movement of the trigger device, a dispensing wheel having a plurality of recesses to hold playing disks, means associated with the dispensing wheel to release disks from successive 20 recesses as they reach one point during rotation of the dispensing wheel, pawl mechanism normally effective in locking the dispensing wheel against rotation, an electromagnet in series with the trigger switch effective to release the locking 25 means so that the dispensing wheel may rotate, a reciprocating member effective to cause rotation of the dispensing wheel, and a switch effective to cause deenergization of the magnet when the reciprocating member reaches one end 30 of its path.

35 20. A machine of the class described comprising a trigger switch, a dispensing wheel, locking means normally preventing rotation of the dispensing wheel, said dispensing wheel having a series of recesses from which playing disks may be emitted when successive recesses reach a given 40 point during rotation of the wheel, means operable in response to actuation of the trigger switch to release said locking means, a manually operable plunger effective to rotate the dispensing wheel for a predetermined fraction of a revolution, and a cutout switch operable in response to movement of the plunger to alter the condition of said last-named means, thus to interrupt the 45 maintenance of said locking means in released condition, whereby the dispensing wheel may be relocked.

50 21. Mechanism of the class described comprising a common support, a control instrumentality mounted upon the support and arranged to be actuated by a ball or the like, a normally inoperative, dispensing mechanism, electrical means operable in response to actuation of said instrumentality to release said dispensing mechanism for operation, and control means mounted upon the support and including a body of electrically conductive liquid operatively associated with the electrical means, said control means being effective to prevent operation of said first-named 55 means when the support is tilted, thereby preventing release of the dispensing mechanism in response to improper actuation of the instrumentality by a ball or the like due to tilting of the support.

60 22. A machine of the class described comprising a playing board, a plurality of trigger devices associated with the board and adapted to be actuated by a ball or the like passing over the board, a normally inoperative, playing disk-releasing mechanism, electrical control means ef-

fective to make said mechanism operable in response to the actuation of the trigger devices, said mechanism including a dispensing wheel rotatable through a fraction of a revolution to emit playing disks, and a switch operable in response to movement of the dispensing wheel when the latter moves to dispense playing disks, the operation of said switch rendering said control means ineffective, thus preventing repeated movements of the dispensing wheel to emit disks.

10

23. A machine of the class described comprising a casing, a playing board enclosed thereby, a game playing instrumentality capable of operation upon insertion of a playing disk into the casing, a trigger switch associated with the board 15 and capable of being actuated under certain conditions of play, a dispensing wheel shaped to receive disks, means to direct inserted disks to the wheel, said wheel being movable to a disk-emitting position, locking means to prevent movement 20 of the wheel toward said position, means operable in response to actuation of the trigger switch to release said locking means, and a manually operable handle effective to rotate the dispensing wheel to said position.

25

24. A machine of the class described comprising a casing, a playing board enclosed thereby, a game playing instrumentality capable of operation upon insertion of a playing disk into the casing, a trigger switch associated with the board 30 and capable of being actuated under certain conditions of play, a dispensing wheel shaped to receive disks, means to direct inserted disks to the wheel, said wheel being movable to a disk-emitting position, locking means to prevent movement 35 of the wheel toward said position, means operable in response to actuation of the trigger switch to release said locking means, a pinion connected to the wheel, a manually operable rack to rotate the pinion and cause the wheel to move 40 to said position, and a cut-out switch actuatable by the rack to cause return of the locking means to normal position, whereby repeated actuations of the rack and movements of the wheel are prevented.

45

25. Mechanism of the class described, comprising a playing board, a trigger switch arranged to be actuated by a ball projected over the board, a normally inoperative, dispensing mechanism, electrical controlling means making the mechanism operable in response to actuation of said switch, said controlling means including a switch automatically operable in response to tilting of the board thereupon to prevent said trigger switch from causing the dispensing mechanism 55 to be operable, thereby preventing improper operation of the dispensing mechanism due to the tilting of the board to cause a ball to actuate the trigger switch.

50

26. Mechanism of the class described, comprising a playing board, a trigger switch arranged to be actuated by a ball projected over the board, a normally inoperative, dispensing mechanism, electrical controlling means making the mechanism operable in response to actuation of said 60 switch, said controlling means including a switch automatically operable in response to tilting of the board thereupon to prevent said trigger switch from causing the dispensing mechanism to be operable, thereby preventing improper operation 65 of the dispensing mechanism due to tilting of the board to cause a ball to actuate the trigger switch, means operable in response to the insertion of a playing disk to release balls for projection over the board and to cause said last-named switch to 70

75

return to normal condition, so that the dispensing mechanism may thereafter be rendered operable in the normal manner.

27. Mechanism of the class described, comprising a playing board having ball-receiving openings, a trigger switch arranged to be actuated by a ball projected over the board and into one of the openings, a normally inoperative, dispensing mechanism, electrical controlling means making the mechanism operable in response to actuation of said switch, said controlling means including a tilting control switch automatically operable in response to tilting of the board thereupon to prevent said trigger switch from causing the dispensing mechanism to be operable, thereby preventing improper operation of the dispensing mechanism due to the tilting of the board, a sliding panel movable in response to the insertion of a playing disk and permitting balls to drop through said openings and to be released for another projection over the board, a switch closed when the panel is thus slid, and an electromagnet which is arranged to be energized when said last-named switch is closed, said magnet having an armature operatively associated with the tilting control switch so that energization of the magnet restores said switch to normal condition.

28. A machine of the class described, comprising a playing board, a plurality of trigger devices associated with the board and adapted to be actuated by a ball passing over the board, a normally inoperative, playing disk returning mechanism, a slide upon which a playing disk may be placed and inserted into the machine upon movement of the slide, means operable in response to such a movement of the slide to release balls for projection over the playing board, means to direct a playing disk thus inserted to the dispensing mechanism, electrical control means effective to make said mechanism operable in response to the actuation of the trigger devices, said mechanism including a dispensing wheel rotatable to emit playing disks, a cut-out switch operable in response to movement of the dispensing wheel when the latter moves to dispense a playing disk, the operation of said switch rendering said control means ineffective thus to prevent repeated movements of the dispensing wheel to emit successive disks, and means responsive to another movement of the slide with a playing disk thereon to return said cut-out switch to normal condition, whereby the dispensing mechanism may be ready for operation following a subsequent actuation of a trigger device.

29. A machine of the class described, comprising a playing board, a trigger switch actuatable by a ball projected over the board, a normally inoperative, playing disk dispensing mechanism, means operable upon insertion of a playing disk to release balls for projection over the board and to direct the inserted disk to said mechanism, electrical control means operatively connecting said mechanism and the trigger switch so that actuation of the latter renders said mechanism operable to dispense playing disks received from said first-named means.

30. A machine of the class described, comprising a playing board, a trigger switch actuatable by a ball projected over the board, a playing disk returning mechanism, means operable upon insertion of a playing disk to release balls for projection over the board and to direct the inserted disk to said mechanism, locking means associated with said mechanism and normally preventing

operation thereof, manually operable means to actuate said mechanism, and electrical control means operable in response to actuation of said trigger switch to release the locking means so that the dispensing mechanism may be manually operated. 5

31. A machine of the class described comprising a playing board, a set of trigger switches electrically connected in series and actuatable by balls projected over the board, a normally inoperative, playing disk return mechanism, means operable upon insertion of a playing disk to release balls for projection over the board and to direct the inserted disk to said mechanism, electrical control means operative when all of said switches are actuated to render the dispensing mechanism operable to dispense playing disks received from said first-named means. 10

32. A machine of the class described comprising a game playing assembly, means to receive a playing disk and release the assembly for operation, and disk returning mechanism, said mechanism including a wheel, said wheel having a plurality of disk receiving openings, a plunger to rotate the wheel through a fraction of a revolution, locking means normally preventing movement of the plunger, said locking means being releasable upon operation of the playing assembly in a given manner, the plunger then being movable inwardly to rotate the wheel in one direction to permit an opening or openings in the wheel to receive disks and movable outwardly to cause the wheel to rotate in the opposite direction to emit disks thus received into an outlet duct, and delay means operatively connected to the wheel to prevent the rapid movement of the plunger. 20

33. A machine of the class described comprising a game playing assembly, disk receiving means arranged to release the assembly for operation when a playing disk is received by the machine, switch means operable when the game is played in a certain manner, disk returning mechanism including a manually actuatable plunger, a wheel rotatable through a fraction of a revolution in response to actuation of the plunger, means to supply disks to said openings and vent disks from the openings to the exterior of the machine, an electromagnet controllable by said switch means, and an armature associated therewith movable to release the plunger and wheel and permit their movement through a limited distance thus to emit disks to the exterior of the machine, and delay means operatively connected to the wheel to prevent the rapid movement of the plunger. 40

34. A machine of the class described comprising a pin board, means associated with the board adapted to be actuated when articles, such as balls, rolled over the board engage said means, electrical switches operable in response to actuation of said means normally to cause the closing of an electrical circuit, a playing disk-dispensing mechanism normally operable in response to current passing through said circuit, a master switch in said circuit, and control means therefore, said last-mentioned means being operable when the board is tilted out of normal position to cause opening of the master switch and interruption of the flow of current through the circuit, whereby operation of the disk-dispensing mechanism in response to actuation of said first-named means is prevented. 60

35. A machine of the class described comprising a board having a plurality of openings there- 70

in, trigger elements associated with certain openings, each arranged to be actuated when an article, such as a ball, passes into the corresponding opening, a switch associated with each trigger element, an electrical circuit in which said switch is located, playing disk-dispensing mechanism operable in response to flow of current through said circuit, a master switch in said circuit, and control means for said master switch responsive to tilting of the board and effective to cause opening of the master switch and prevent flow of current to the disk-dispensing mechanism.

36. Mechanism of the class described comprising a common support, a control instrumentality arranged to be actuated by a ball or the like, a dispensing mechanism, means operable in response to actuation of said instrumentality to render said dispensing mechanism operable, and tilting control means effective to prevent operation of said mechanism when the support is improperly tilted to bring the ball into operating relation with said instrumentality. 5 10
